UNITED STATES PATENT OFFICE.

ROYAL MARCHER, OF NEW YORK, N. Y., ASSIGNOR TO COHN & ROSENBERGER, INC., OF NEW YORK, N. Y., A CORPORATION OF NEW YORK.

DESIGN FOR A HAIR-RIBBON HOLDER.

52,051.

Specification for Design.

Patented May 21, 1918.

Application filed March 2, 1918. Serial No. 220,062. Term of patent 14 years.

To all whom it may concern:

Be it known that I, ROYAL MARCHER, residing in the city, county, and State of New York, have invented a new, original, and ornamental Design for Hair-Ribbon Holders, of which the following is a specification, reference being had to the accompanying drawing, forming part hereof, in which—

Fig. 2 is a side elevation of the same, and
Fig. 3 is an end view of the same.

I claim:

The ornamental design for a hair ribbon holder, as shown.

ROYAL MARCHER.
